Alvan Andrew his atty,

UNITED STATES PATENT OFFICE.

DANIEL MURRAY, OF SALEM, MASSACHUSETTS.

THILL-COUPING.

SPECIFICATION forming part of Letters Patent No. 357,221, dated February 8, 1887.

Application filed July 21, 1886. Serial No. 208,690. (No model.)

To all whom it may concern:

Be it known that I, DANIEL MURRAY, a citizen of the United States, and a resident of Salem, in the county of Essex and State of 5 Massachusetts, have invented new and useful Improvements in Shaft-Couplings, of which the following, taken in connection with the accompanying drawings, is a specification.

This invention relates to improvements in 10 shaft-couplings, and it is carried out as follows, reference being had to the accompanying drawings, wherein—

Figure 1 represents a plan view of the invention, showing the cap as removed. Fig. 15 2 represents a longitudinal section on the line A B, shown in Fig. 1; and Fig. 3 represents a cross-section on the line C D, also shown in Fig. 1.

Similar letters refer to similar parts wherever they occur on the different parts of the drawings.

a represents the clasp, having the downwardly-projecting screws a' a", as usual, and nuts a" a", by means of which and the yoke b the clasp 25 is firmly secured to the carriage-axle in the ordinary manner. In one piece with the clasp a is made the forwardly-projecting bearing-block a³, provided with a cap, c, that is secured to the block a³ by means of screw-bolts d d, passing loosely through perforations in the cap c and screwed into and through tapped perforations in the block a³, as shown in Fig. 2, 30 and furthermore secured to the said block by means of check-nuts d' d', as shown, to prevent their being loosened by the jar of the carriage-axle.

e represents the shaft-iron, secured by means of bolts to the shaft, as usual. In one piece with the shaft-iron e is made the ball e', resting in half-spherical sockets a⁴ c', made, respectively, in the bearing-block a³ and cap c, as shown, said ball having horizontal cylindrical trunnions e" e", adapted to turn in corresponding recesses in the block a³ and cap c, 45 as shown in Figs. 1 and 3, such trunnions forming extensions of the rear forked end of the shaft-iron e, as shown in Fig. 1.

E is a perforation in the shaft-iron e, between its rear end and the ball e', to allow 50 the shaft-iron to be swung freely up and down without interfering with the front edges of the block a³ and cap c.

e³ is an annular groove on the ball e', as shown in the drawings, such groove being semicircular, or nearly so, in form, and adapted to receive the cylindrical portion of the respective fastening-bolts d d, as shown in Figs. 1 and 2, and by this arrangement the ball e' is retained in the sockets c' a⁴ with a proper frictional resistance to prevent the common rattling.

In case the ball e' or its sockets should become worn, the cap c may be removed and its under side or the upper side of block a³ ground off in proportion to the wear, and the different parts put together, as shown in Fig. 2.

As an equivalent means of adjustment, a thin washer or plate may originally be confined between the cap and block, which washer may be filed or ground off from time to time 70 to compensate for the wear of the ball in its sockets.

The shanks of the bolts d d may be made slightly tapering, instead of cylindrical, without departing from the essence of my invention.

This my invention is very simple in construction and is entirely devoid of steel or rubber springs so common in most of the well-known shaft-couplings. It is positive in its action, very strong and wear-resisting, easy of lubrication, the groove in the ball serving as an oil-receptacle to contain a proper amount of lubricant, and by the device as described 75 all rattling of the parts is avoided.

Having thus fully described the nature, construction, and operation of my invention, I wish to secure by Letters Patent and claim—

The herein-described improved shaft-coupling, consisting of the clasp a and its socketed bearing-block a³, and the socketed cap c, secured to block a³ by means of screw-bolts d d, combined with the shaft-iron e, having in its rear end a grooved ball, e', journaled in the cap and block and adapted to receive the bolts d 90 d, as and for the purpose set forth.

In testimony whereof I have signed my name to this specification, in the presence of two subscribing witnesses, on this 7th day of July, A. D. 1886.

DANIEL MURRAY.

Witnesses:

ALBAN ANDRÉN,
WILLIAM B. FLANAGAN.
